CARBURETOR

Robert F. Bracke, Chicago, Ill.

Application February 20, 1935, Serial No. 7,332

8 Claims. (Cl. 261—72)

My invention pertains to carburetors and is particularly concerned with carburetors of the fuel lift type. The invention disclosed and claimed in this application is an improvement 5 over that disclosed and claimed in my prior application, Serial No. 6,421, filed February 14, 1935.

Under certain peculiar atmospheric conditions, difficulty was experienced with the carburetor of 10 my said prior application as a result of moisture condensing from the air and freezing on the secondary air valve, thereby temporarily rendering this air valve incapable of carrying out all 15 of its normal functions in an efficient manner. An object of my present invention is to provide a carburetor wherein the secondary air valve is so located relative to the vaporization of the fuel that this air valve is not subjected to the chilling effect of such vaporization.

20 Another object of my invention is to provide a carburetor having improved means for controlling the secondary air valve during choking of the engine.

Another object of my invention is to provide a 25 carburetor having improved means for cracking the throttle during choking of the engine.

Another object of my invention is to provide a carburetor wherein the detrimental effects of backfiring are minimized.

30 Another object of my invention is to provide a carburetor having improved means for controlling the degree of suction obtaining in the fuel chamber.

Another object of my invention is to provide a 35 carburetor having improved means for preventing fluttering of the secondary air valve.

Another object of my invention is to provide a carburetor having improved means for guiding the secondary air valve to prevent cocking 40 thereof.

Other objects and advantages will become apparent as the description proceeds.

In the drawings,

Figure 1 is a vertical section through a carburetor embodying my invention;

Figure 2 is a vertical section taken on the line 2—2 of Figure 1;

Figure 3 is a vertical section taken on the line 3—3 of Figure 1;

50 Figure 4 is a horizontal section taken on the line 4—4 of Figure 1;

Figure 5 is a vertical section taken on the line 5—5 of Figure 2;

Figure 6 is a vertical section through the upper 55 end of a modified form of my invention; and

Figure 7 is a diagrammatic showing of a carburetor embodying my invention.

Referring to Figures 1 to 5, inclusive, of the drawings, I have illustrated my carburetor as comprising three main castings A, B and C, held together by bolts 10, there being suitable gaskets 12 and 14 clamped between the castings to provide an air-tight assembly.

Fuel enters the carburetor through an inlet 16 adapted to be connected to a main fuel tank by 10 suitable piping. The fuel entering the inlet 16 passes into a filter chamber 18 in which there is provided any suitable filtering means, such, for example, as that disclosed in my said prior application. From the filter chamber 18 the fuel 15 passes to a fuel chamber 20 containing a float 22 guided for vertical movement on a cylinder 24. The float 22 controls the usual inlet valve, not shown, through which fuel is admitted into the fuel chamber 20.

The primary air supply enters through a tube 26 whose upper end is adapted to be inserted into a suitable opening in any conventional type of air filter and silencer of the kind now commonly used on automobiles. The air entering the tube 26 passes into a nozzle Venturi tube 28 having a restricted throat terminating in a step just below which are the diagonal fuel feed passages 30. These passages 30 connect the throat of the nozzle 28 with an annular chamber 32 communicating with a passage 34. The passage 34 in turn communicates with the fuel chamber 20 by way of orifice 36 and cylinder 24. The piston 38 of the accelerator pump is provided with suitable ports whereby fuel may be drawn from the fuel chamber to the throat of the nozzle 28.

The fuel entering the nozzle 28 through feed passages 30 mixes with the primary air and forms an incompletely vaporized mixture which is discharged from the lower end of the nozzle 40 into duct 40. The duct 40 has a cylindrical outlet 42 leading into the upper end of the mixing chamber 44 where the mixture of fuel and air delivered by the nozzle 28 mixes with secondary air.

This secondary air enters the carburetor through horn 46 which has a reduced upper end adapted to be received in the same air filter and silencer which covers the entrance to the primary air tube 26. In the horn 26 is a throat member 50 held in place by a spring clip 50. Throat member 48 has the internal shape of a large Venturi tube and is shown as being closed by a secondary air valve 52 which is held in the elevated position shown in Figure 1 by a spring 54 resting in the 55

base of a cup-shaped guide 56. Stops 53 limit the upward movement of the valve 52.

The guide 56 is urged downwardly against a transverse beam-like portion 58 of casting A by spring 60 whose upper end rests against the in-turned flange of a sheet-metal stop 62. The lower end of stop 62 extends to a point just above the base of guide 56 and limits the upward movement of guide 56 when a backfire occurs. The in-turned upper end of the stop 62 rests against a spring clip 64 secured in a suitable groove in sleeve 66.

The secondary air valve 52 is drawn downwardly against the resistance of spring 54 under the influence of the suction obtaining in the mixing chamber 44. The interior of air valve 52 is in constant communication with the upper end of mixing chamber 44 through tube 68, annular chamber 70, and restricted orifice 72.

20 A pair of throttle bores 74 and 76 communicate with the lower end of mixing chamber 44. Throttle bores 74 and 76 are provided with throttle valves 78 and 80, respectively, both of these valves being mounted on a common shaft 82 connected 25 with the usual accelerator pedal by means of an arm 84, and also connected with the usual hand throttle control by means of a second arm 86.

When the throttle valves 78 and 80 are in the position corresponding to idling operation of the 30 engine, these valves almost, but not quite, close the throttle bores 74 and 76.

Piston 38 of the accelerator pump is urged downwardly by spring 88 and is moved upwardly by piston rod 90 resting at its lower end on an adjustable plug 92 carried by arm 94 of a lever 96 having a second arm 98 connected by link 100 to branch 102 of lever 84 which oscillates with the throttle valve shaft 82. Piston 38 carries an economizer 104 having an enlarged and tapered 40 upper end which restricts the flow of fuel through the knife-edged orifice 36 when the engine is idling and when it is operating under part throttle. When the engine is operating in full throttle, the reduced lower end of the pin 104 is located 45 in the orifice 36 and permits free flow of fuel to the nozzle 28.

The piston 38 of the accelerator pump is provided with an inner series of ports 106 above which is a disk 108 held against the upper ends 50 of the ports 106 by the force of gravity when the engine is idling or idle. The disk 108 has a small orifice 110 through which fuel is supplied to the engine when it is idling, but when the engine is operating at part throttle the disk 108 is sucked upwardly away from the ends of ports 106 to permit a greater flow of fuel therethrough.

Piston 38 also includes relief means for preventing over-supply of fuel to the nozzle 28 when the throttle is suddenly opened over a wide range 60 of throttle movement. This relief means comprises a second series of ports 112 whose lower ends are normally closed by a ring 114 urged against them by a light spring 116. This spring 116 yields when the throttle is suddenly opened 65 over a wide range of throttle movement and permits back flow of fuel through the piston 38.

Part of the air entering the horn 46 passes downwardly outside of throat member 48 and into ducts 118 and 120 communicating with a restricted orifice 122 in choke plate 124. A sheet-metal cup 126 forms a chamber 128 on the side of choke plate 124 which is opposite ducts 118 and 120. Air from chamber 128 can pass through a second opening 130 in choke plate 124 and thence through 70 tubular member 132 into booster Venturi tube

134. Tubular member 132 carries a spring ring 133 which prevents the tubular member from dropping out when the choke plate 124 is removed. Booster 134 has a restricted throat terminating in a shallow step just beyond which are radial passages 136 which connect the throat of the booster with an annular space 138. The space 138 communicates through a passage 139 with the upper end of the fuel chamber 20.

Booster 134 discharges into duct 140. Air and any vapor which may be discharged into duct 140 passes through orifice 142 and lateral outlets 144 into the stream of secondary air which enters the carburetor around the secondary air valve 52.

It is important that the suction in the fuel chamber 20 be maintained constant under all normal conditions of engine operation, and for this purpose I provide a pin 146 having an enlarged head clamped between the air valve 52 and a plate 148 supported by spring 54. The lower end of the pin 146 is tapered and is located in orifice 142 so that as the suction in the mixing chamber 44 increases, the air valve 52 is lowered. A larger portion of the pin 146 enters orifice 142 and restricts the outlet for the booster 134 so that a substantially constant degree of suction is maintained in the duct 140 located between the orifice 142 and the outlet of the booster. When the secondary air valve 52 is in lowered position, the lower end of pin 146 is received in a tube 150.

Between idling speed and an engine speed corresponding to approximately twenty miles per hour of vehicle travel, is a range requiring delicate control of the booster outlet. It is therefore desirable to have a relatively large movement of the restricting pin 146 during this range so that extreme accuracy of adjustment can be avoided. I therefore so design the throat member 48 and secondary air valve 52 that a relatively large movement of this air valve occurs 40 between these engine speeds, and this large movement of the air valve produces an equally great movement of the restricting pin 146 whose tapered lower end lies in the orifice 142 through which the booster discharges.

The desired idling setting of the carburetor is obtained by controlling the degree of suction existing in the chamber 128. This chamber communicates with the engine side of throttle valves 78 and 80 by way of duct 152, port 154, bore 156, 50 passage 158 and opening 130 in choke plate 124. A needle valve 160 controls this communication and this needle valve 160 constitutes the idling adjustment for the carburetor.

Figure 5 shows the position of the opening 130 55 when the choke plate 124 is in normal position. It will be noted that as the choke plate is shifted from normal to part choke position, the opening 130 restricts the flow of air from chamber 128 into booster 134 but always maintains communication between chamber 128 and suction passage 158. When the choke plate 124 is moved to the position of full choke, the opening 130 is moved entirely away from the inlet end of booster 134 and a very small orifice 162 is located opposite 65 the inlet end of the booster and forms the sole source of air supply for the booster. The choke plate 124 is connected with the usual manual choke control through ball-ended arm 164.

Choke plate 124 has a centrally located non-circular opening 166 in which is located the non-circular end of a shaft 168. The other end of this shaft carries fingers 170 and 172 which are formed from a single strip of metal and are yieldably connected to the shaft 168 for rotation 75

therewith by a coil spring 174. Each finger has an outer end lying below and in alignment with one side of the lower end of the air valve 52, so that when the choke plate 124 is rotated the fingers 170 and 172 are first brought into light yielding engagement with the lower end of air valve 52. The greater the rotation of choke plate 124, the greater the force with which these fingers are urged against the air valve 52 to hold it in closed position. When the choke plate 124 is moved to full choke position, a pin 176 engages and forms a rigid connection between finger 172 and shaft 168 and positively holds the air valve 52 against opening. The pin 176 projects from a collar 177 which is secured to the shaft 168 by the same screw which secures one end of spring 174 to this shaft.

The upper end of duct 152 communicates with a transverse passage 178 (Figure 4) which is normally closed by shaft 168. Shaft 168 has an opening 180 therethrough and when the choke plate 124 is moved to part or full choke position, shaft 168 is turned so that opening 180 lies in part or full alignment with passage 178, depending upon the degree of application of the choke. This establishes communication between the space immediately below air valve 52 and the engine side of the throttle valves 78 and 80 and has the same general effect as cracking the 30 throttle valves 78 and 80.

In the operation of my improved carburetor the primary air enters tube 26 from the air cleaner and silencer and passes into nozzle 28. A vacuum is created in the throat of the nozzle 35 28 and draws fuel from fuel chamber 20. This fuel flows through diagonal feed passages 32 in the nozzle 28 and mixes with the primary air to form an incompletely vaporized mixture which passes into mixing chamber 44. The suction existing in mixing chamber 44 when the engine is operating normally draws the secondary air valve 52 downwardly and secondary air flows into the mixing chamber 44 around the air valve 52.

Further vaporization of the fuel takes place in the mixing chamber 44, and the vaporized mixture flows past the partly or full open throttle valves 78 and 80 to the engine. When the throttle valves are opened through an appreciable range of movement, the piston 38 is raised and injects an additional quantity of fuel into the nozzle 28, to permit rapid acceleration of the engine. If the throttle valves are opened suddenly through a wide range of their movement, the relief means in the piston 38 will act to prevent an over-supply of fuel to the nozzle 28.

When the engine is idling or is operating at less than half of its full speed, the secondary air entering through the throat member 48 and 60 around the air valve 52 creates an area of maximum suction which is located a short distance below the largest diameter of the air valve. However, when the speed of the engine is increased to approximately half of its full speed or thereabove, this point of maximum suction is transferred to that space immediately below the narrowest portion 182 of the mixing chamber 44. This is the point at which the nozzle 28 discharges into the mixing chamber 44, and this 65 feature of my invention results in maximum efficiency of the nozzle 28 at the higher engine speeds.

As the suction in the mixing chamber increases, the secondary air valve 52 is lowered an amount 75 proportional to this increase in suction and the

pin 146 correspondingly restricts the outlet for the booster Venturi tube so that a constant degree of suction is maintained on the fuel chamber 20. This likewise contributes to the efficiency of the nozzle 28 at high engine speeds. The consumption of excess fuel at idling and low speeds is prevented by the economizer pin 36.

When the choke is applied, the inlet to the booster Venturi tube is restricted, and the degree of suction obtaining in the fuel chamber 20 is 10 accordingly reduced. This results in a greater pressure drop between the fuel chamber and the throat of the nozzle 28 so that the nozzle 28 provides a richer mixture which facilitates starting and running of the engine when it is cold. 15

Application of the choke also opens a by-pass around the throttle valves which connects the space immediately below the air valve 52 with the engine side of the throttle valves. At the same time this by-pass is created, the fingers 170 20 and 172 are so moved as to resist to a greater or less degree the opening of secondary air valve 52. This combination produces a high degree of suction in the space below the air valve 52 and produces an increased discharge of fuel and air 25 by the nozzle 28. Some of this mixture flows to the engine past throttle valves 78 and 80 which are always slightly open, and the rest reaches the engine by way of the by-pass around these valves. The additional fuel supplied to the engine 30 through the use of the by-pass tends to prevent stalling of the engine when it is cold.

My invention also contemplates means in the form of stop 62 to protect the carburetor against back-fire of the engine such as might occur during any period of engine operation. If the sheet metal stop 62 were not provided to limit the upward movement of the guide 56, upward movement of this guide under the sudden force of a back-fire would either cause the upper end of 40 this guide to engage the inner shoulder provided by the secondary air valve 52, or would compress and be stopped by springs 54 and 60. If the upper end of the guide 56 were driven forcefully against the inner shoulder of the secondary air 45 valve, the upper end of the guide 56 would be distorted and forced outwardly against the secondary air valve with the result that this air valve would stick and fail to operate properly. On the other hand, if the force of the explosion were 50 exerted upon the springs 54 and 60, these springs might be distorted to such an extent that injury would result and again the smooth operation of the secondary air valve would be impaired.

In Figure 6 I have shown, in cross-section, the 55 upper end of a modified form of my invention. In this form the horn 184 supports a dash-pot cylinder 186 containing a piston 188 mounted on the upper end of piston rod 190 which reciprocates with secondary air valve 192.

The piston 188 and cylinder 186 constitute an air dashpot for preventing fluttering of the secondary air valve 192. The tendency of this air valve to flutter is particularly great when the air valve is only slightly open and the dashpot which 65 I have provided is particularly effective under these conditions. When the air valve 192 has moved an appreciable distance from closed position, the piston 188 uncovers the upper end of a passage 194 which permits a limited amount of 70 air to enter the upper end of cylinder 186 and reduces the dashpot action of the cylinder and piston.

The modification shown in Figure 6 also has the further advantage of providing improved 75

guiding means for the air valve 192 to prevent cocking of this air valve. The lower portion 196 of the piston rod 190 is guided in the sleeve 198 which corresponds to the sleeve 66 of the embodiment shown in Figure 2, whereas the upper end of the piston rod is guided by the piston 188 so that there is a guide for this piston rod on each side of the valve 192. It is to be understood that the extreme lower end of the piston rod 196 has the same tapered conformation as the lower end of pin 146 in Figure 2 and performs the same function that this pin performs. Except for the distinctions which I have mentioned, it is to be understood that the modification shown in Figure 15 is identical with that shown in the first five figures of the drawings.

It is to be understood that my invention is not limited to the specific structure shown in the drawings but that my invention may assume 20 various forms and that the scope of my invention is to be limited solely by the following claims.

I claim:

1. In a carburetor of the class described, the combination of a nozzle, a primary air inlet for 25 supplying air to said nozzle, a fuel chamber from which said nozzle is supplied, a booster for creating suction in said fuel chamber, a valve for admitting secondary air, a pin operated by said valve and controlling the degree of suction 30 created by said booster in said fuel chamber, a tube for receiving the end of said pin, said tube being located some distance from said valve, a discharge conduit for said nozzle surrounding said tube, said discharge conduit terminating in 35 a mixing chamber wherein the mixture delivered by said nozzle mixes with secondary air admitted past said valve, said mixing chamber being of reduced cross-section adjacent the discharge end of said conduit, and valve means for connecting 40 said mixing chamber with a source of suction.

2. In a carburetor of the class described, the combination of a nozzle, a source of fuel supply therefor, a primary air inlet for said nozzle, a secondary air valve, a spring for closing said 45 valve, said valve being opened by a pressure differential created on the opposite sides thereof, a mixing chamber into which said nozzle and secondary air valve discharge, a throttle bore communicating with said mixing chamber, a valve 50 in said bore, a by-pass passage around said last named valve, a finger for resisting opening of said air valve, a shaft for moving said finger into and out of engagement with said air valve, said shaft intersecting said by-pass passage, and 55 a port in said shaft controlling said by-pass passage.

3. In a carburetor of the class described, the combination of a nozzle, a source of fuel supply therefor, a mixing chamber into which said 60 nozzle discharges, a primary air inlet for said nozzle, a secondary air valve for admitting additional air to said mixing chamber, said air valve being spaced from said mixing chamber, a throttle bore communicating with said mixing 65 chamber, a throttle valve in said bore, a by-pass connecting the engine side of said throttle bore with the space between said mixing chamber and said secondary air valve, choke means for enriching the mixture supplied by said nozzle, 70 and a valve in said by-pass controlled by said choke means.

4. In a carburetor of the class described, the combination of a nozzle, a source of fuel supply therefor, a primary air inlet for said nozzle, a 75 secondary air valve, a movable cup-shaped guide

for said air valve, resilient means for holding said guide in normal position, and other means for limiting movement of said guide away from normal position in the event of a backfire.

5. In a carburetor of the class described, the combination of a nozzle, a source of fuel supply therefor, a primary air inlet for said nozzle, a secondary air valve, a movable cup-shaped guide for said valve, a cup-shaped stop located in said guide, a support for said stop, and a spring 10 confined between the bottom of said cup-shaped guide and the bottom of said cup-shaped stop, said spring maintaining said guide in normal position.

6. In a carburetor of the class described, the combination of an air valve having a seat of Venturi tube form, a mixing chamber to which air is supplied past said air valve, said mixing chamber having a part formed like a Venturi tube, a nozzle discharging into said mixing chamber 20 at a point adjacent that part of the mixing chamber formed as a Venturi tube, a float chamber from which said nozzle is supplied with fuel, a booster Venturi tube for creating a suction in said float chamber, said booster Venturi tube 25 discharging into said mixing chamber, and means operated by said air valve for controlling communication between said booster Venturi tube and said mixing chamber, said air valve Venturi tube determining the point of greatest suction 30 when the engine to which the carburetor is attached is operating at low speeds and said mixing chamber Venturi tube determining the point of greatest suction when said engine is operating at high speeds.

7. In a carburetor of the class described, the combination of an air inlet formed of a large Venturi tube, a valve located in said inlet, a mixing chamber communicating with said inlet and having a portion formed as a large Venturi 40 tube, a nozzle discharging into said portion of the mixing chamber, a fuel chamber constituting a source of fuel supply for said nozzle, a booster for creating a suction in said fuel chamber, said booster discharging into said mixing chamber 45 intermediate said Venturi tubes, and means operated by said inlet valve for controlling communication between said booster and said mixing chamber.

8. In a down draft carburetor of the class described, the combination of a mixing chamber, a nozzle Venturi tube discharging into said mixing chamber, said nozzle Venturi tube constituting a primary air inlet for said mixing chamber, a source of fuel supply for said nozzle Venturi tube, an air valve for admitting secondary air to said mixing chamber, a throttle bore for connecting said mixing chamber with a source of suction, a throttle valve in said throttle bore, said air valve being separate from said nozzle Venturi tube and being mounted for movement responsive to variations in the degree of suction existing in said mixing chamber, a pneumatic dashpot cylinder supported above said air valve, a piston fitting said cylinder with sufficient 60 closeness to produce a dashpot action when said cylinder is filled with air, a piston rod, a connection between said piston rod and said air valve, and means comprising a single restricted atmospheric vent communicating with said cylinder adjacent one end thereof for decreasing the effectiveness of said dashpot when high degrees of suction obtain in said mixing chamber.
